UNITED STATES PATENT OFFICE.

JOHN WANAT, OF PITTSBURGH, PENNSYLVANIA.

COMBINATION TOY.

1,394,456.

Specification of Letters Patent. Patented Oct. 18, 1921.

Application filed October 1, 1920. Serial No. 414,043.

To all whom it may concern:

Be it known that I, JOHN WANAT, a citizen of the United States of America, residing at Pittsburgh, in the county of Allegheny and State of Pennsylvania, have invented certain new and useful Improvements in Combination Toys, of which the following is a specification.

This invention relates to certain new and useful improvements in combination toys and has particular reference to an improved toy of simple construction adapted to be manipulated with respect to its various parts so as to provide selectively and at will either a pop gun, a water gun or a reed noise gun.

The principal object of the invention is to provide a toy which may be readily converted from a pop gun to a water gun.

Another object of the invention is to provide a toy which may be readily converted from a pop gun to a reed noise gun.

Still another object of the invention is to provide a water gun which may be readily converted into a reed noise gun.

Other objects will appear as the nature of the invention is better understood, and the same consists in the novel form, combination and arrangement of parts herein-after more fully described, shown in the accompanying drawings and claimed.

In the drawings, wherein like reference characters designate corresponding parts throughout the several views,

Figure 1 is a substantially central longitudinal sectional view, partly broken away, of a toy constructed in accordance with the present invention with its parts disposed to provide a pop gun,

Fig. 2 is a view partly in side elevation and partly in longitudinal section and partly broken away of the device shown in Fig. 1 with its parts arranged to provide a water gun,

Fig. 3 is a view similar to Fig. 2 with the parts disposed to provide a reed noise gun,

Fig. 4 is an enlarged front end view of the device as shown in Fig. 3,

Fig. 5 is an enlarged transverse sectional view taken substantially upon line V—V of

Fig. 1,

Fig. 6 is a view similar to Fig. 4 with the stopper turned for use as a pop gun in accordance with Fig. 1, and

Fig. 7 is an enlarged elevational view of the forward end of the barrel of the toy.

Referring more in detail to the several

views, the present invention consists of a barrel 5 within which is reciprocably mounted a piston head 6 having a central port 7 in communication with the longitudinal bore 8 of a tubular piston rod 9 which carries said head 6. A handle section 10 is threaded upon the outer end of the piston rod 9 and has a bore 11 communicating with the bore of the piston rod 9. The bore of the section 10 is enlarged and the wall thereof threaded for detachably receiving the screw threaded end 12 of another section 13 of the handle which is also provided with an angular port 14 communicating with the port 11 and with the atmosphere. A suitable form of reed 15 in the form of a slotted plate is arranged within the enlarged portion of the bore of the handle section 10 and is clamped against the shoulder 16 of the latter by the inner end of the handle section 13 which is screwed into the section 10.

The bore 7 of the piston head 6 is threaded for detachable reception of a plug 17 for a purpose which will presently become apparent. A stopper 18 somewhat similar to the ordinary form of pop gun stopper is frictionally received in the forward end of the barrel 5 and has a port 19 through the center thereof adapted to be closed at its outer end by means of a threaded plug 20.

The forward end of the barrel 5 is provided with an annular groove 21 for permitting one end of a cord 22 or the like to be conveniently secured to the barrel, and the other end of said cord is attached by means of an eye 23 to the stopper 18. A pair of angular keepers 24 are rigid with the forward end of the barrel 5, and a pair of lugs 25 project radially from and are rigid with the stopper 18 whereby when the stopper 18 is positioned as shown in Figs. 2, 3 and 4, the lugs 25 are arranged behind the keepers 24 for retaining the stopper 18 within the end of the barrel 5, and whereby, when the stopper is positioned as shown in Figs. 1 and 6, said stopper 18 may be forced outwardly of the barrel 5 upon operation of the piston 6 in the usual manner of operating a pop gun,

If it is desired to use the device as a pop gun, the plugs 17 and 20 are positioned as shown in Fig. 1 and the handle composed of sections 10 and 13 is pulled so as to withdraw the piston rod 9. Said handle is then forced in the opposite direction for moving the head 6 inwardly of the barrel 5, thus

80

85

90

95

100

105

110

compressing the air and forcibly projecting the stopper 18 out of the end of the barrel 5 whereby the usual popping noise is produced.

5 If it is desired to use the device as a water gun, the plug 17 is left in place and the plug 20 is removed as shown in Fig. 2, while the stopper 18 is turned from the position of Fig. 6 to the position of Fig. 4. Water 10 may then be readily drawn into the barrel 5 through the port 19 and forced outwardly through the same as will be apparent.

When using the device as a reed noise gun, the plug 20 is replaced and the plug 17 is 15 removed, while the stopper 18 is left in its position of Fig. 4. Upon forcing the piston head and piston rod inwardly when the parts are thus disposed, the air is forced through the ports 7 and 8 as well as through 20 port 11, the slots of the reed 15 and port 14 to the atmosphere, whereby a noise is produced in accordance with the type of reed employed.

It is thus to be seen that I have provided 25 a very simple form of combination toy which will provide the amusement of three separate toys now available, a consideration making the invention of considerable merit and salability.

30 It is believed that the construction and operation as well as the advantages of the present invention will be readily understood and appreciated by those skilled in the art from the foregoing description.

35 Minor changes may be made without departing from the spirit and scope of the invention as claimed.

What is claimed as new is:—

1. A combination toy of the class described comprising a tubular barrel, a piston head reciprocable within said barrel, means to reciprocate said piston head, a stopper 40 removably positioned in the forward end of the barrel and having a port therethrough, means to open or close said port, and means to detachably fasten said stopper within the end of said barrel whereby the device may be selectively employed as a pop gun or a water gun at will.

45 2. A combination toy of the class described comprising a tubular barrel, a piston head reciprocable within said barrel, means to reciprocate said piston head, a stopper removably positioned in the forward end of the barrel and having a port therethrough, means to open or close said port, means to detachably fasten said stopper within the end of said barrel whereby the device may 50 be selectively employed as a pop gun or a water gun at will, said piston rod and said piston head having communicating ports leading from the interior of the barrel to the atmosphere, a reed arranged in the path of air passing through said piston rod to the 55 atmosphere, and means to open or close the

port of the piston head whereby the device may be further employed as a reed noise gun upon retention of the stopper in the end of the barrel and upon closing of the port through the stopper when the port through 70 the piston head is opened.

3. A combination toy including a tubular barrel, means to open or close the forward end of said barrel, a piston rod and a piston head reciprocable in the barrel and having ports providing communication therethrough from the interior of the barrel to the atmosphere, a reed arranged in the path of the air passing from the piston rod to the atmosphere, and means to open or close the port of the piston head whereby when the forward end of the barrel is open and the last named port is closed the toy may be employed as a water gun, and whereby when the forward end of the barrel is closed and said last named port is open, the device may be employed as a reed noise gun.

4. The combination with a barrel and means closing the forward end thereof, of a piston head and a piston rod reciprocable 90 within the barrel and having ports therethrough providing communication from the interior of the barrel to the atmosphere, and a reed arranged so as to be in the path of the air passing from the barrel to and through the piston rod to the atmosphere 95 when the piston rod is reciprocated.

5. The combination with a barrel and means closing the forward end thereof, of a piston head and a piston rod reciprocable 100 within the barrel and having ports therethrough providing communication from the interior of the barrel to the atmosphere, a reed arranged in the path of the air passing from the piston rod to the atmosphere, and a handle upon the outer end of said piston rod carrying said reed.

6. The combination with a barrel and means closing the forward end thereof, of a piston head and a piston rod reciprocable 110 within the barrel and having ports therethrough providing communication from the interior of the barrel to the atmosphere, a reed arranged in the path of the air passing from the piston rod to the atmosphere, and a handle upon the outer end of said piston rod carrying said reed, said handle comprising a female and a male section threaded together with the reed clamped therebetween.

7. The combination with a barrel and means closing the forward end thereof, of a piston head and a piston rod reciprocable 125 within the barrel and having ports therethrough providing communication from the interior of the barrel to the atmosphere, a reed arranged in the path of the air passing from the piston rod to the atmosphere, a handle upon the outer end of said piston rod carrying said reed, said handle comprising

ing a female and a male section threaded together with the reed clamped therebetween, and said male section of the handle having an angular port communicating with 5 the port of the piston rod and with the atmosphere.

8. In a combination toy of the class described, the combination with a piston carrying barrel and a stopper frictionally and detachably positioned within the forward end thereof, angular keepers rigid with the forward end of the barrel and radially projecting rigid lugs carried by said stopper whereby when the stopper is in one position said 15 lugs are disposed behind said keepers for retaining the stopper within the end of the barrel, and whereby said stopper may be forcibly projected from the end of the barrel when the stopper is rotated a part of a revolution for bringing said lugs from behind 20 said keepers.

9. A combination toy of the class described comprising a pressure creating means including a barrel, a stopper removably positioned in the forward end of the barrel and having a port therethrough, means to open or close said port, and means 25 to detachably fasten said stopper within the

end of said barrel whereby the device may be selectively employed as a pop gun or a 30 water gun at will.

10. A combination toy of the class described comprising a pressure creating means, a stopper projectable by said pressure creating means, and means associated 35 with the stopper and the pressure creating means for selectively converting the device for use as a pop gun or a water gun at will.

11. A combination toy including a pressure creating means, a stopper projectable 40 thereby, a reed operable by said pressure creating means, and means associated with the pressure creating means to render the stopper or the reed inoperative at will.

12. A combination toy including a pressure creating means having a ported member through which water may be forced by said means, a reed operable by said pressure creating means, and means to render said 45 reed operative or inoperative at will including means for closing the port of said member whereby the device may be selectively employed as a water gun or a reed noise gun at will.

In testimony whereof I affix my signature. 55
JOHN WANAT.
